(57) The ornamental design for a purse, as shown and described.

DESCRIPTION

FIG. 1 is an isometric view of a purse showing my new design;

FIG. 2 is a front view of the purse, the rear view being a mirror image therefore;

FIG. 3 is a left side view of the purse;

FIG. 4 is a right side view of the purse;

FIG. 5 is a top plan view of the purse; and,

FIG. 6 is a bottom plan view of the purse.

The dash-dash broken lines illustrating a wristlet loop form no part of the claimed design.

The broken lines on the top of the design illustrate unclaimed stitching.
